S. H. HARRIS

DISPLAY BOARD OR SIMILAR ARTICLE

Filed May 10, 1926

INVENTOR.

SAMUEL H. HARRIS.

BY

Richard D. Down

ATTORNEY.

UNITED STATES PATENT OFFICE.

SAMUEL H. HARRIS, OF BROOKLYN, NEW YORK.

DESIGN FOR A DISPLAY BOARD OR SIMILAR ARTICLE.

Application filed May 10, 1926. Serial No. 17,624. Term of patent 3½ years.

To all whom it may concern:

Be it known that I, SAMUEL H. HARRIS, a citizen of the United States, residing in Brooklyn, county of Kings, and State of New York, have invented a new, original, and ornamental Design for Display Board or Similar Article, of which the following is a specification, reference being had to the accompanying drawing, forming part thereof, in which the figure is a view in perspective of the display board or similar article.

I claim:

The ornamental design for a display board or similar article as shown.

SAMUEL H. HARRIS. [L.S.]
